FRANK LOWELL BUTLER, OF CHICAGO, ILLINOIS.

ELECTRICAL FIXTURE.

1,384,427.

Specification of Letters Patent. Patented July 12, 1921.

Application filed March 8, 1920. Serial No. 364,356.

To all whom it may concern:

Be it known that I, FRANK LOWELL BUTLER, a citizen of the United States, and a resident of Chicago, in the county of Cook and State of Illinois, have invented a new and useful Improvement in Electrical Fixtures, of which the following is a full, clear, and exact description.

My invention relates to improvements in electric fixtures, and it consists in the combinations, constructions and arrangements herein described and claimed.

An object of my invention is to provide an electrical fixture in which means is provided for insulating electrical conducting means from the parts maintaining such electrical conducting means in position.

A further object of my invention is to provide in a device of the type described a novel form of insulating member.

A further object of my invention is to provide a device of the type described that is ornamental in appearance, durable in construction, and thoroughly practical commercially.

Other objects and advantages will appear in the following specification, and the novel features of the invention will be particularly pointed out in the appended claims.

My invention is illustrated in the accompanying drawings, forming part of this application, in which—

Figure 1 is a vertical central section through the device,

Fig. 2 is a section along the line 2—2 of Fig. 1,

Fig. 3 is a section along the line 3—3 of Fig. 1,

Fig. 4 is a section along the line 4—4 of Fig. 1,

Fig. 5 is a vertical central section through a modified form of the device.

In carrying out my invention, I make use of a pipe or conduit 1, which projects from a wall or ceiling. A coupling 2 has a threaded opening 3 formed in its upper end for screwing on the threaded end 4 of the pipe or conduit 1. A socket 5 is formed in the lower end of the coupling 2 and is adapted to receive an enlarged upper end 7 of an insulating member 6. An annular recess 8 is provided in the inner wall of the socket 5 near its lower end. A spring member 11 is partly disposed within the annular recess 8 and projects partly there-

from to press upwardly against the lower side of the enlarged end 7 of the insulating member 6, thereby maintaining the latter in position. An abutment 9 projects inwardly from the inside of the wall of the socket 5 and is adapted to enter a recess 10 provided in the enlarged upper end 7 of the insulating member 6, thereby preventing the latter from being rotatably moved.

A bolt 12 has its head 13 embedded within the insulating member 6 and a threaded shank 14 depending therefrom. A bushing 15 has a central bore divided by a partition 16 into an upper portion 17 and a lower portion 18. The upper portion 17 is screwed on the threaded shank 14 of the bolt 12. The lower portion of the bushing 15 is enlarged to form a shoulder 19 in which a slot 20 is provided. The upper end of the bushing 15 is threaded exteriorly at 21 for a purpose to be hereinafter set forth. A stem 22 has its upper end seated within the slot 20. A rod 23 has an end screwed within the portion 18 of the bushing 15 and extends through the stem 22. A nut 24 is screwed on the lower end of the rod 23. The nut 24 has an annular slot 25 adapted to receive the lower end of the stem 22 which is supported thereby. An eye member 26 is formed integral with the nut 24 and engages a link 27 which in turn supports a socket (not shown) for an electric light or other electrical element. An opening 28 is formed through each side of the nut 24, as shown in Fig. 4. Insulated wires 29 are arranged to enter the stem 22 through lateral openings 30 provided in the stem near its upper end. The wires 29 extend through the stem 22 and are passed through the openings 28, extending to the socket (not shown). A canopy 31 is slidably disposed upon the stem 22 and may be secured at any desired point therealong by means of a screw 32.

From the foregoing description of the various parts of the device, the operation thereof may be readily understood. The insulating member 6 thoroughly insulates the electrical conducting wires 29 from the coupling 2 and the pipe or conduit 1. Consequently, current cannot pass along the conduit 1 to the walls of the building to cause fire should short circuiting occur. The bushing 15 is threaded exteriorly and is therefore adapted for screwing into an insulating joint of an ordinary construction if it

is desired to use the bushing 15 and the parts depending therefrom with such an insulating joint.

In the modified form of the device shown 5 in Fig. 5 of the accompanying drawings, the construction of the parts is identical with the construction of the form of the device illustrated in Fig. 1 with the exceptions about to be set forth, and I have therefore 10 designated corresponding parts throughout by the same reference numerals.

Instead of the bushing 15 I provide a bushing 40 which has a smaller threaded central bore 41 adapted for screwing on the 15 threaded shank of the bolt 12. The bushing 40 has a larger threaded central bore 42 adapted to receive the threaded end of a pipe 43. A nut 44 is screwed on the lower end of the pipe 43 and is provided with a 20 flanged shoulder 45 adapted to support a canopy 46. It will be obvious that when the nut 44 is screwed on the end of the pipe 43, the canopy 46 will be pushed tightly against a ceiling or wall and held firmly in position. A plurality of links 47 are secured to the sides of the canopy 46. Supporting means (not shown) for chandeliers and the like are suspended from the links 47.

The device is simple in construction, ornamental in appearance, and provides an efficient means for preventing an electrical current from passing into the walls of a building in which installed.

I claim:

- 35 1. In an electrical fixture, a fixed supporting member, a coupling having its upper end secured thereto, said coupling having a socket formed in its lower end, an insulating member having an enlarged top portion, 40 said top portion being disposed within said socket, an abutment projecting from the inside of said socket and arranged to enter a recess provided in the upper portion of said insulating member to prevent the latter 45 from being rotatably moved, a spring member partly disposed within an annular recess in the inner surface of said socket at a point immediately beneath the enlarged portion of said insulating member, whereby 50 said insulating member is maintained in position, a bolt having a non-circular head embedded in said insulating member and arranged to depend therefrom, a bushing having its upper end secured to the depending 55 end of said bolt, said bushing having its lower end formed into a shoulder, a stem having its upper end seated against said shoulder, said stem having lateral openings therethrough near its upper end, a rod having 60 its upper end secured to the lower end of said bushing and being arranged to extend through said stem, a nut screwed on the lower end of said rod, said nut being provided with a shoulder adapted to support 65 the lower end of said stem, an eye member formed integral with said nut, a canopy slidably disposed on said stem, means for securing said canopy in position along said stem, and current carrying wires arranged to enter 70 said stem through said lateral openings and to pass from said stem through diametrically opposed openings provided through said nut. 75
3. In an electrical fixture, the combination 115 of a fixed supporting member, a coupling secured thereto, said coupling being provided with a socket in its lower end, an insulating member having an enlarged top portion disposed within said socket, an abutment projecting from the inside of said socket arranged to enter a recess provided in said insulating member to prevent the latter from being rotatably moved, means for maintaining said insulating member in engagement with said socket, a bolt having 120 its head embedded in said insulating member and arranged to depend therefrom, and means carried by said bolt for supporting 125 an electrical socket or the like. 130
4. In an electrical fixture, the combination 130

formed integral with said nut, a canopy slidably disposed on said stem, means for securing said canopy in position along said stem, and current carrying wires arranged to enter said stem through said lateral openings and to pass from said stem through diametrically opposed openings provided through said nut. 70

2. In an electrical fixture, a fixed supporting member, a coupling having its upper end secured thereto, said coupling having a socket formed in its lower end, an insulating member having an enlarged top portion, 80 said top portion being disposed within said socket, an abutment projecting from the inside of said socket and arranged to enter a recess provided in the upper portion of said insulating member to prevent the latter from being rotatably moved, a spring member partly disposed within an annular recess in 85 the inner surface of said socket at a point immediately beneath the enlarged portion of said insulating member, whereby said insulating member is maintained in position, a bolt having a non-circular head embedded in 90 said insulating member and arranged to depend therefrom, a bushing having its upper end secured to the depending end of said bolt, said bushing being threaded both interiorly and exteriorly and having its lower 95 end formed into a flanged shoulder, a stem having its upper end seated against said shoulder, said stem having lateral openings therethrough near its upper end, a rod having 100 its upper end secured to the lower end of said bushing and being arranged to extend through said stem, a nut screwed on the lower end of said rod, said nut being provided with a shoulder adapted to support the lower end of said stem, an eye member 105 formed integral with said nut, a canopy slidably disposed on said stem, means for securing said canopy in position along said stem, and current carrying wires arranged to enter 110 said stem through said lateral openings and to pass from said stem through diametrically opposed openings provided through said nut. 115

3. In an electrical fixture, the combination 120 of a fixed supporting member, a coupling secured thereto, said coupling being provided with a socket in its lower end, an insulating member having an enlarged top portion disposed within said socket, an abutment projecting from the inside of said socket arranged to enter a recess provided in said insulating member to prevent the latter from being rotatably moved, means for maintaining said insulating member in engagement with said socket, a bolt having 125 its head embedded in said insulating member and arranged to depend therefrom, and means carried by said bolt for supporting an electrical socket or the like. 130

of a fixed supporting member, a coupling secured thereto, said coupling being provided with a socket in its lower end, an insulating member having an enlarged top portion, said top portion being disposed within said socket, an abutment projecting from said socket and positioned to enter a recess provided in said insulating member to prevent the latter from being rotatably moved, means for maintaining the enlarged top portion of said insulating member within said socket, a bolt having a non-circular head embedded in said insulating member and arranged to depend therefrom, a bushing secured to the depending end of said

bolt, a stem having its upper end seated against said bushing, said stem being formed with lateral openings therethrough near its upper end, a rod having its upper end secured to said bushing and being arranged to extend through said stem, a nut screwed on the lower end of said rod, said nut being adapted to support said stem and being provided with vertical extending slots in its sides, a canopy slidably disposed on said stem, and electrical conducting wires arranged to enter said stem through said lateral openings and to pass from said stem through the slots provided in said nut.

FRANK LOWELL BUTLER.
